WEFT BEAT-UP MECHANISM OF LOOMS FOR WEAVING

Derrick Walter Shimwell, Alderley Edge, England

Application February 16, 1944, Serial No. 522,609

In Great Britain February 26, 1943

5 Claims. (Cl. 139—191)

This invention relates to weft beat-up mechanism of looms for weaving and has for its object to provide improved beat-up mechanism which allows of the speeding up of the loom cycle without increasing the speed of the shuttle through the shed and without the necessity of altering the shuttle race or track. The invention relates particularly to looms of the type in which beat-up is effected by a comb like part separate from the reed, the latter taking no part in the beat-up operation.

In accordance with my present invention, the beating-up comb enters the warp threads adjacent to the reed from above, travels to the beat-up point and then withdraws with an upward movement from the warp threads and returns to its entry point in order to perform the next beat-up operation.

My invention further comprises the arrangement in which the beat-up comb withdraws from the beat-up position with a combined backward and upward movement.

The comb teeth may enter the shed immediately in front of the dents of the reed or in the case where the reed dents are staggered, immediately adjacent to the back row of dents so that they come behind any loose end or ends which may gather in front of the reed. The comb may enter the shed when it is closed or may overtake the upper row of warp threads as they move downwards to the closed position so prolonging the portion of the loom cycle during which the shuttle can be in the shed. The comb may be traversed back and forth by members sliding on rods at opposite sides of the warp threads, and be given a pivotal movement to bring it into the warps and to withdraw it therefrom after beating-up.

The loom shuttle may be of the free or fly type, in which no control is exercised over its movements between shuttle boxes or be of the controlled or captive type, as used in narrow fabric and needle looms.

Referring to the accompanying explanatory drawings—

Figures 1 and 2 show two different positions of one form of weft beat-up mechanism constructed and arranged in accordance with this invention.

Figure 3 is a view similar to Figure 1 but showing a modified arrangement of beat-up mechanism.

Figure 4 is a detail sectional view on the line A—B of Figure 3.

Figure 5 is a plan view of Figure 1.

In Figures 1 and 2, *a* indicates the slay sole upon which the shuttle *b* rides as it passes through the warp shed. The upper and lower rows of warp threads *c* and *d* constitute the shed. *e* indicates the reed which is carried by the slay sole. Both reed and slay sole are stationary and take no part in the beat-up operation.

Beat-up is effected by a comb *f*, the teeth of which have the same spacing as the dents of the reed *e*.

The comb *f* is detachably secured by studs as *g* upon arms *h* (one at each side of the loom) secured upon a spindle *i*, to which also are secured arms as *j*, so that the arms *h* and *j* turn together about the axis of the spindle *i*. The latter is journalled in bearings in slides as *k*, one at each end of the spindle *i*, the slides being capable of movement along guide bars as *m*, each carried in a bracket *n* secured to the slay sole and in a bracket *o* of the side frame of the machine.

Each slide *k* is reciprocated along its guide bar *m* by a link *p* pivotally connected to the spindle *i* and to an arm *q* fulcrumed at *r* in the side frame of the loom, the arm *q* being oscillated by the crank pin *s* and link *t*. The crank shaft is indicated at *s'*. Upon a projecting part *u* of the link *t* is pivoted one end of a link *v* which is connected to one arm *w* of a bell crank lever pivoted to the arm *q*, the other arm *x* of such lever being connected by the link *y* to the arm *j* before referred to.

Figure 1 shows the comb *f* as it is about to enter the closed shed. It will be seen that its end is close to the reed so that the teeth of the comb can enter the spaces between the warp threads produced by the reed dents. The comb then travels with its end in the path indicated by the track *4*. When the comb gets to the beat-up position as shown in Figure 2, the shed has opened and the shuttle can commence its return flight through the shed. As the comb completes its forward movement, the crank arm *s*² comes into line with the link *t* and there is very little movement of the slide *k* for a considerable angular movement of the crank arm *s*², but during such angular movement, the projecting part *u* of the link *t* is imparting a relatively considerable angular movement to the bell crank lever *w*, *x* and the arm *j* with the result that the comb is turned in an anti-clockwise direction about the spindle *i* and so has an upward movement which draws it clear of the upper row of warp threads whilst the comb travels backwards to a position adjacent

the reed when a reverse action takes place and the comb is lowered into the shed.

It will be seen that the fact that the beat-up comb is positioned for movement into the warp threads from above avoids any special form of slay sole *a* and the need for holding the shuttle against the reed in its flight due to the necessity for cutting down the dimensions of the slay sole and for gapping it to enable the teeth of the comb to come right up to the dents of the reed in order to enable the teeth to enter correctly between the warp threads. In addition, the comb teeth can commence to enter the warp shed before the shuttle has completely left the shed which is not the case when the comb teeth enter the shed from below in which case the shuttle must be clear of the warp space before the shuttle can enter.

In the modification shown in Figure 3 the slides *k* are reciprocated on the bars *m* (one at each side of the loom) by two links or connecting rods *5* each connected to a crank pin *6* on a crank arm *7* secured to a crank shaft *8*. Each connecting rod *5* has a fulcrum pin *9* secured therein eccentrically with relation to the crank pin *6* and upon such pin *9* is journalled the end of the rod *10* which is coupled to the arm *j*. With this arrangement as with that in Figures 1 and 2, the arm *j* is given a considerable angular movement at the ends of the traverses of the slide *k* in order to raise the beat-up comb out of the warp shed when beat-up is completed and to reintroduce it adjacent to the reed *e*. The path of the point of the comb is indicated by the track *4* as in Figures 1 and 2.

With my improvement, the portion of the loom cycle (360°) occupied by the shuttle traverse or flight may be increased to as much as about 270° so that the cycle can be speeded up without the necessity for increasing the speed of the shuttle. As will be appreciated it is impossible to increase the shuttle speed economically and safely.

What I claim is:

1. Weft beat-up mechanism for a loom of the type in which the reed does not effect beat-up, comprising a beat-up comb, and means for guiding and moving said comb through a closed path in which it enters the warp threads adjacent to the reed from above, travels to the beat-up point and effects beat-up, and then withdraws with an upward movement from the warp threads and

returns to its entry point in order to effect the next beat-up operation.

2. Weft beat-up mechanism as claimed in claim 1 in which the beat-up comb has both a reciprocatory and a pivotal movement, the pivotal movement giving upward and downward movements to the comb at about the ends of its traverses.

3. Weft beat-up mechanism as claimed in claim 10 1 for a loom having a reed which does not effect beat-up, wherein said comb is secured upon arms upon a spindle journalled in reciprocating slides above the warp shed, the slides being reciprocated each from a crank pin, and the spindle being 15 turned about its axis when the slides are at and about the ends of their traverses by means connected to fulcrum points upon the links (which effect the reciprocation of the slides) offset with relation to the connection of said links to the 20 crank pins which impart the back and forth movements to said links.

4. Weft beat-up mechanism as claimed in claim 11, comprising slides, bars disposed above the warp shed (one at each side of the loom) upon which 25 the slides reciprocate, a spindle journalled at its ends in said brackets secured upon said spindle, a beat-up comb carried by said brackets, connecting rods connected to said spindle at one end and to crank pins at the other end, arms upon 30 the ends of said spindle, further connecting rods each connected to one of said arms at one end and to a crank pin at the other end which is secured in one of the first mentioned connecting rods adjacent to the connection of the latter to its crank pin.

5. Weft beat-up mechanism for a loom of the type in which the reed does not effect beat-up, comprising a beat-up comb arranged above the warp threads, and means to impart a compound movement to said comb having one component substantially parallel to the weft threads and the other component substantially perpendicular thereto whereby said comb enters the warp threads adjacent to the reed from above, travels 40 to the beat-up point and effects beat-up, and then withdraws with an upward movement from the warp threads and returns to its entry point in order to effect the next beat-up operation.
